UNITED STATES PATENT OFFICE.

CHARLES O. HATHAWAY AND FRANCIS W. HUFFAKER, OF BIG TIMBER, MONTANA.

TRACE-FASTENER.

1,014,000.

Specification of Letters Patent.

Patented Jan. 9, 1912.

Application filed May 15, 1911. Serial No. 627,202.

To all whom it may concern:

Be it known that we, CHARLES O. HATHAWAY and FRANCIS W. HUFFAKER, citizens of the United States, residing at Big Timber, 5 in the county of Sweet Grass, State of Montana, have invented a new and useful Trace-Fastener, of which the following is a specification.

Our invention relates to improvements in 10 trace-fasteners for whiffletrees.

The invention has for its object primarily to provide for the ready attachment and detachment of the trace to and from a whiffletree, respectively.

15 A further object is to effectively guard against the casual disengagement or detachment of the trace from its carrying or securing hook.

A still further object is to carry out these 20 ends in a simple, expeditious and effective way.

The invention consists of certain instrumentalities and features substantially as hereinafter fully disclosed and defined by 25 the claims.

In the accompanying drawing illustrating the preferred embodiment of our invention, wherein it will be understood that various changes and modifications may be made as 30 relate to the details of the construction and arrangement of the parts without departing from the spirit of the invention, Figure 1 is a front elevation of the device. Fig. 2 is a plan view thereof. Fig. 3 is an inverted, 35 or underside view of the same. Fig. 4 is a transverse section, produced upon the line $x-x$ of Fig. 1, viewing inwardly. Fig. 5 is also a transverse section of like general parts, a hinged or articulated connection, 40 however, being effected between the strap-members forming the clasp or retainer for the trace-carrier.

In practicing our invention, we suitably provide a fastener or retainer, designated 45 generally as 1, for the retention of the trace upon the whiffletree-hook 2, as against the casual disengagement or detachment of said trace therefrom, while said fastener is readily actuated for the attachment and detachment 50 of the trace to and from the whiffletree-hook as may be required in the practical use thereof. Said fastener or retainer 1 includes in its construction preferably an inflexible or metal-strap member having 55 preferably the formation disclosed particularly by Figs. 1 and 3 and being to a lim-

ited extent springy or resilient. Said strap or member has an end vertical portion 3 which is opposed to the end of the whiffletree-hook 2, said vertical portion being outwardly bent to form a recess 4. Said bent portion or recess receives said whiffletree-hook, upon its outer edge, perpendicular to the horizontal plane thereof, the inner surface of the recess or bent portion closely 60 engaging said edge of said hook to prevent the casual disengagement at that point of the trace and accordingly providing for effectively securing the trace against accidental release or detachment, as is apparent. 65 Said vertical end-portion 3, has a short lower horizontal extension preferably split or bifurcated, it thus being formed into two branches or prongs simply, however, as an expediency, as will appear presently. Said 70 branches terminate in eyes 6 which receive preferably a screw-headed and nut-equipped bolt 7; and to the whiffletree 8 is suitably held a thin metal-plate or strap 9 having an eye-terminal 10 at one end receiving or encompassing the bolt 7, intermediate the eyes 6 as a convenient or expedient way of effecting such connection; and upon which bolt the fastener or retainer 1 is thus fulcrumed or pivoted. The vertical 75 end portion of the fastener or retainer is extended at its upper extremity into a lever or handle forming portion 11 which is preferably of resilient character, to aid its retention in position. Said lever or handle member is held in effective or locked position 80 by engagement with a catch 12 adapted to be suitably secured to the whiffletree 8. The catch 12 is preferably comprised of opposed 85 arcuate sections or members 13, 13^a adapted to be conjointly clamped upon the whiffletree, the lower end of said catch, being preferably extended a short distance downwardly, as at 14. Between the downwardly 90 extended portions 14 is interposed a short arcuate or curved connection, or bar-like member 15, engaging the underside of the strap 9 and also having downwardly extending portions 16. The downward extensions 14 and the corresponding extensions 16 of 95 the clasp members or sections 13 are connected together preferably also by a screw-headed and nut-equipped bolt 17 inserted therethrough. The upper end of the clamp member or section 13^a terminates in a short 100 vertical extension 18 suitably bolted or secured as at 19 to a like extension 20, effect-

ing connection between the upper horizontal overhanging portion forming the clip proper. This clip, together with an additional clip-member 21, also embracing the 5 whiffletree 8, also provides for the retention of the strap 9 in place thereon, the additional clip-member, preferably having similar lower-end downward extensions 22. Also a like short connection or bar-like member 23 10 is applied to engage the underside of the strap 9 and interposed between the downward extensions 22 of the additional clip-member 21. The member 23 also has downward extensions 24 which are suitably 15 cured or bolted to the extensions 22 of the clip 21, as at 25.

As suggested by Fig. 5, in lieu of the form of clip disclosed above, as in Fig. 4, a clip 26 may be employed. Said clip is preferably formed of two sections or members 27 and 28, hinged or articulated together preferably after substantially the fashion of forming the pivotal connection 6, 7 between the retainer or fastener 1, and the strap-member 9; said hinge, or articulated connection between the members or sections 27 and 28, being formed as follows: The member or section 27 is bifurcated to form the same with branches or arms having eye-ended terminals 29 while the lower or opposed end terminates in an eye which is received between the eye-ended terminals 29. A preferably screw-headed and nut-equipped bolt 30 is inserted through the eye-ended terminals and eye for completing the hinging or articulating connection. The member 28 has a lower end depressed portion 31 adapted to form a seat to receive the strap-member 9 to aid in effecting the retention of the latter in place upon the whiffletree. The members 27 and 28 of the clip 26 are connected or held together above the whiffletree by means of a suitably headed and nut-equipped bolt 32 passed through 45 apertures of upper end straight portions 33 and 34 corresponding to the portions 18 and 20 of the form of clip shown particularly by Fig. 4 of the preferred disclosure of the invention.

50 It is clearly apparent from the foregoing description and accompanying illustration or drawing, that we have provided a device of this character which is adapted to allow of the ready engagement and disengagement of the trace with and from the whiffletree hook or carrying member, also which will effectively secure the trace against possible causal detachment therefrom. The device is also characterized by simplicity, 55 embracing but few parts, is readily applied for use, and easily actuated, while it is inexpensive to manufacture.

It will be readily appreciated that the application or attachment of the device to the whiffletree may be effected so that the resilient handle forming extension or member of the trace-retainer 1 may be opposed to the front side of the whiffletree, or otherwise, as may be required.

We claim:—

1. A device of the character described, including the combination with a whiffletree and a trace-carrier, of a trace-retainer having a recess-forming vertical portion to receive the trace-engaging end of said trace-carrier, said vertical portion having a lower-end inturned-horizontal extension, means effecting pivotal connection for said vertical portion with respect to the whiffletree, said vertical portion having in continuation of its upper end a resilient handle-forming extension, and means for the connection of said handle-forming extension to the whiffletree.

2. A device of the character described, including the combination with a whiffletree and a trace-carrier, of a trace-retainer having a recess-forming vertical portion adapted to receive the trace-engaging end of said trace-carrier, a strap-member applied to said whiffletree, upon one side thereof, means effecting pivotal connection between said strap-member and an inturned or horizontal extension of said vertical portion, said vertical portion having in continuation of its upper end a resilient handle-forming extension, and means for the connection of said handle-forming extension to said whiffletree.

3. A device of the character described embracing the combination with a whiffletree and a trace-carrier of a trace-retainer having a handle-forming extension and adapted to engage the outer or face end of said trace-carrier, means for the manipulation of said trace-retainer, a strap-member applied to said whiffletree, means effecting pivotal connection between said strap-member and said trace-retainer, and means for the attachment of said strap-member to said whiffletree including clips applied to the latter and said strap member, one of said clips having an overhanging catch-forming portion for engaging the handle-forming extension of said trace-retainer.

In testimony that we claim the foregoing as our own, we have hereto affixed our signatures in the presence of two witnesses.

CHARLES O. HATHAWAY.
FRANCIS W. HUFFAKER.
